UNITED STATES PATENT OFFICE.

FRANK M. MORTON, OF PHENIX CITY, ALABAMA.

REMOVABLE CHECK VALVE.

Application filed November 25, 1921. Serial No. 517,656.

To all whom it may concern:

Be it known that I, FRANK M. MORTON, a citizen of the United States, residing at Phenix City, in the county of Lee and State 5 of Alabama, have invented certain new and useful Improvements in Removable Check Valves; and I do declare the following to be a full, clear, and exact description of the invention, such as will enable others skilled in 10 the art to which it appertains to make and use the same.

My invention relates to improvements in check valves designed primarily for use in connection with air compressors, and has 15 reference more particularly to valves which are readily removable to be replaced by others or to be repaired. Numerous attempts have heretofore been made to provide a check valve which can be quickly and easily 20 removed whenever desired, but most of these devices have employed several disconnected parts which must be separately removed and are subject to loss. It is the aim of my invention however to provide an extremely 25 simple, yet a highly efficient arrangement, in which the check valve, the valve seat, the valve cage, and the closing spring for the valve are all embodied in a single unit which is bodily removable from or applicable to an 30 air compressor, water pump or like machines.

With the foregoing and minor objects in view, the invention resides in the novel subject matter hereinafter described and 35 claimed, the descriptive matter being supplemented by the accompanying drawing.

Figure 1 is a vertical sectional view of an air compressor equipped with two of the valve units, the inlet valve being shown almost entirely in vertical section, while the 40 exhaust valve is partially in elevation.

Figure 2 is an enlarged side elevation of one of the valve units removed from the compressor.

Figure 3 is a top plan view of the unit shown in Fig. 2.

Figure 4 is a bottom plan view.

In the drawing above briefly described, I have shown an air compressor provided 50 with a compression chamber 1, a plunger 2 movable through one side of said chamber, a crank 3 and connecting rod 4 for reciprocating said plunger, an air intake 5 and an air exhaust 6. All of these parts may be of the 55 usual or any desired construction and con-

stitute no part of the present invention. Each passage 5-6 is provided with an annular ledge 7 and in parallel spaced relation with said ledge with a removable plate 8 held in place by cap-screws or the like 9. 60 Interposed between each plate 8 and the ledge 7 associated therewith, is one of the improved valve units 10 and since both of these units are identical, only one will be described in detail. 65

The valve unit 10 includes a seat 11 which is preferably in the form of a ring of L-shape cross section as shown clearly in Fig. 1, said ring being here shown as provided with one or more spider arms 12 which may 70 well have a central enlargement 13. A valve cage rests upon the seat-ring 11 and preferably consists of an end plate 14 adjacent the plate 8, and a suitable number of legs 15 integral with said plate 14 and having their 75 lower ends disposed in contact with the seat-ring. The cage and the valve seat are secured together, the valve and the valve spring are housed within said cage, and all 80 of these parts are so assembled as to form a single unit to be bodily attached or detached. In the present showing, a tie-bolt 16 is employed to secure the valve cage to the seat-ring, said bolt extending through the enlargement 13 of the arm or arms 12 85 and through the center of the plate 14. The check-valve 17 which is positioned within the cage, is slidably mounted on and guided by the tie-bolt 16 and the closing spring 18 for 90 said valve surrounds said bolt, one end of said spring acting against the valve while its other end reacts against the plate 14. 95

When applying the valve unit 10, the plate 8 is removed, said unit is inserted into the machine, the seat-ring 11 is properly positioned upon the ledge 7, the plate 8 is again applied, and a number of set-screws 19 which pass through said plate are tightened so as to securely hold the unit in place. Whenever it is necessary to remove any part of the valve mechanism for repairing or to entirely replace the unit by an undamaged unit while repairs are being made, the operation just described is, of course, reversed and an interchange of valves may be quickly effected so that the compressor is only out of 100 operation for a negligible length of time. 105

Since excellent results may be obtained from the details disclosed, they are preferably followed, but within the scope of the 110

invention as claimed, numerous changes may be made.

I claim:

A removable check valve unit comprising
5 a valve cage having a head plate and elongated arms extending from said head plate, a valve seat engaging the free ends of said arms and having a central opening and fluid passages about the central opening, a connecting bolt extending axially of the cage and passing through the center of the head plate and through the central opening of

said valve seat to securely hold the valve seat in contact with said arms, a check valve freely slideable upon said bolt between said head plate and valve seat, and a spring coiled about said bolt having one end engaging said head plate and the other engaging said check valve to yieldably hold the check valve in engagement with said valve seat and close the fluid passages thereof. 15 20

In testimony whereof I have hereunto set my hand.

FRANK M. MORTON.
